(57) **CLAIM**

The ornamental design for handbag with interchangeable front and back panels, as shown.

DESCRIPTION

FIG. 1 is a perspective view of handbag with interchangeable front and back panels showing my new design;

FIG. 2 is a front view thereof;

FIG. 3 is a rear view thereof;

FIG. 4 is side view thereof;

FIG. 5 is another side view thereof;

FIG. 6 is a top view thereof;

FIG. 7 is a bottom view thereof;

FIG. 8 is another perspective view thereof showing the back panel detached from the handbag;

FIG. 9 is another perspective view thereof showing the handbag without the back panel and the front panel partially attached to the handbag;

FIG. 10 is another perspective view thereof showing the handbag without the front panel and the back panel detached from the handbag; and,

FIG. 11 is another perspective view thereof showing the handbag without the front panel and the back panel partially attached to the handbag.

The broken lines depict portions of the handbag with interchangeable front and back panels and form no part of the claimed design.

1 Claim, 9 Drawing Sheets
